KNIT FABRIC

Howard Grady Dickens, Thomasville, N. C., assignor to Scott & Williams, Incorporated, Laconia, N. H., a corporation of Massachusetts

Original application December 6, 1938, Serial No. 244,283. Divided and this application July 29, 1939, Serial No. 287,377

5 Claims. (Cl. 66—173)

This invention relates to knit fabrics and more particularly to circular knit hosiery having an elastic thread engaged at suitable wales of courses of the welt and top and it is an object of this invention to provide a stocking having a welt of plain knit fabric and a stocking top of ribbed fabric knit continuously with the stocking welt, both the welt and top having a continuous elastic thread engaged therewith at desired wales in a number of the courses of the welt and top.

In the drawings:

Fig. 1 is a view of a half-hose knit in accordance with this invention; and

Fig. 2 is a diagram, drawn to a larger scale, of the loops of portions of the welt and top and showing the relation of the elastic thread thereto in fabric in accordance with this invention.

As shown in the drawings, a half-hose knit in accordance with this invention comprises a double-walled plain fabric welt W and a ribbed fabric top T, both knit in the usual manner but having an elastic thread R engaged at wales of the welt and top during the knitting thereof. The plain knit leg L and instep I may have embroidery or wrap patterns thereon, as indicated diagrammatically at P and with a heel H, a double sole S, and the toe U may be knit in the usual manner.

Stockings in accordance with this invention can be knit separately, each completed stocking being dropped from the machine, or they can be knit in a string, being connected by courses of a "draw thread" which permits of the stockings being readily cut apart. The stocking would be knit on a circular knitting machine having cylinder and dial needles and the "draw thread" course would be knit on the alternate cylinder needles which are active during the knitting of the welt and the ribbed top. After a sufficient number of courses of the "draw thread" has been knit, the dial needles are brought into action with the active alternate cylinder needles for one revolution, the dial needles taking bights of the yarn during the one revolution to form, with the active alternate cylinder needles, the make-up or starting course and then being withdrawn to hold the bights of yarn taken while the welt is knit upon the active alternate cylinder needles. At the desired course in the knitting of the welt, the elastic thread is presented to selected needles, alternate ones of the active cylinder needles in the arrangement shown in the drawings, at a point in advance of the feeding points for the wrap and body yarns, the elastic thread be-

ing taken in the hooks of the needles and drawn down to be engaged beneath the webs of web holders and held down when the cylinder needles are raised to take the body yarn. The elastic thread is thus interlaced with the active cylinder needles and brought beneath the latches of the needles to which it was fed so that it is cast off at the usual knitting wave without being knitted. As shown in Fig. 2, the elastic thread is introduced into successive courses of the welt and is interlaced with loops of the fabric so as to cross the sinker loops between adjacent needle wales while lying wholly at the back of the fabric. Thus the elastic thread in the course *i* crosses the sinker loops between the needle wales *c* and *e* and *e* and *g* and lies upon the same side of the loops in the needle wales *c*, *e* and *g*.

The interlacing of the elastic thread with the active cylinder needles continues during the knitting of the welt and after the dial needles are brought forward to again take the body yarn so as to join the ends of the welt and knit rib fabric. Joining the ends of the welt places the elastic thread on the inner face of the wall of the welt. Interlacing the elastic thread with the active alternate cylinder needles during the knitting of the rib top places the elastic thread on the same face of the cylinder needle wales as wales *c*, *e* and *g* of Fig. 2 and on the opposite faces of the intervening dial needle wales, as wales *d* and *f*. In the ribbed fabric, as in the plain fabric, the elastic thread is engaged with the loops of successive courses in successive needle cylinder wales. Thus, the elastic thread at wale *c* is engaged at course *i* in the ribbed fabric and at course *l* in the plain fabric, while at wale *e* it is engaged at course *h* in the ribbed fabric and at course *m* in the plain fabric. This arrangement secures the elastic thread in the fabric and prevents it from creeping in case it is broken.

The elastic thread is engaged in the desired number or all of the courses of the ribbed fabric top and then withdrawn and the ribbed fabric top is then completed. Thereafter the leg L is knit on all the cylinder needles, wrap patterns P being provided if desired and the heel H, instep I, sole S and toe U are knit in the usual manner.

This application is a division of my co-pending application Serial No. 244,283, filed December 6, 1938, now Patent No. 2,174,439.

What is claimed is:

1. Circular knit hosiery having a plain fabric welt and a ribbed fabric top with an elastic thread

- interlaced with the cylinder needle wales in the same manner in the welt and top.
2. Circular knit hosiery having a plain fabric welt and a ribbed fabric top with an elastic thread engaged with loops of different courses in adjacent cylinder needle wales of the welt and top.
3. Hosiery having a plain fabric welt and a ribbed fabric top with needle wales of the welt continued into the top and an elastic thread interlaced with the needle wales of the welt and with the needle wales continued into the top in the same manner.

4. Hosiery having a plain fabric welt and a ribbed fabric top with an elastic thread engaged with loops of different courses in adjacent cylinder needle wales of the welt and top and extending between rib and plain fabric wales in the top. 5

5. Hosiery having a plain fabric welt and a ribbed fabric top with an elastic thread engaged with loops of different courses in adjacent cylinder needle wales of the welt and top.
